UNITED STATES PATENT OFFICE.

DAVID CARLAW, SR., DAVID CARLAW, JR., ALEXANDER LYLE CARLAW,
AND JAMES WHITE CARLAW, OF GLASGOW, SCOTLAND.

NUMBERING ARRANGEMENT FOR USE IN CONNECTION WITH PRINTING AND NUMBERING MACHINES.

No. 811,372.

Specification of Letters Patent.

Patented Jan. 30, 1906.

Application filed July 18, 1905. Serial No. 270,197.

To all whom it may concern:

Be it known that we, DAVID CARLAW, Sr., DAVID CARLAW, Jr., ALEXANDER LYLE CARLAW, and JAMES WHITE CARLAW, residing at 5 Glasgow, Scotland, have invented an Improved Numbering Arrangement for Use in Connection with Printing and Numbering Machines, of which the following is a specification.

10 This invention relates to a numbering arrangement for use in connection with rotary printing and numbering machines such as used for printing and numbering counter check-books, bill-heads, tickets, labels, &c.

15 Under this invention the numbering arrangement comprises a disk or wheel, upon the circumference of which two sets of numbers are arranged, and in order that the numbers may be printed in proper order and position the disk is revolved by suitable mechanism and is also at intervals shifted laterally, so as to alternately bring first the one set of numbers and then the other set of numbers into correct printing position. Of

20 course instead of using one numbering disk or wheel there may be several numbering disks or wheels arranged side by side, and the mechanism would be arranged so as to shift the disks or wheels laterally to the correct 25 printing position. In order that the printing may only take place at a certain point (or points) on the surface of the impression-cylinder, the place or places where it is desired the printing should take place are raised up 30 slightly above the general surface of the cylinder, and the numbering disk or disks are so arranged that the peripheral numbers will only contact with and make an impression on the paper at these raised places.

35 40 The invention may be carried out in various ways without departing from the principle thereof; but in order that the invention may be clearly and precisely understood we will now proceed to describe one arrangement suitable for rotary printing and numbering machines such as used for printing and numbering check-books.

45 The arrangement is illustrated under two modifications on the drawings annexed, 50 whereon—

Figure 1 is a plan view of the numbering mechanism. Fig. 2 is a section taken on the line X X, Fig. 1. Fig. 3 is a section of the numbering-wheel *a*. Fig. 4 shows a modi-

fied arrangement wherein two numbering-wheels are used. 55

In carrying out the invention for a machine adapted to number two sheets in the circumference of the impression-cylinder at each revolution thereof, each sheet being 60 separately numbered, and presuming that the numbers only run up to "50," then we provide a disk or wheel *a* with two parallel circumferential ridges *a*² *a*², each having circumferential projections provided with numbers for the first ridge, odd numbers from "1" to "49," and for the second ridge even numbers from "2" to "50," the numbers *b* being arranged and engraved in any suitable and well-known manner, so as to properly 65 number the sheets and print them longitudinally or transversely, or otherwise. In order that the printing may be done at the correct position on the impression-cylinder *c*, the disk is shifted laterally, so as to bring each 70 ridge alternately into the proper printing position. To effect this, the numbering-disk is mounted on a sleeve *d*, fitted slidably on a shaft *e*, which latter is revolved by means of gearing from the axle *h* of the impression-cylinder, which latter is revolved by gear in the usual manner. The sleeve, which is slotted at *i*, is guided by means of a key *j*, secured to the shaft, and is moved back and forward laterally thereon by means of a jaw *k* on a vibrating lever *l*, which jaw engages with collars *e*' *e*' on the sleeve. The lever, which is fulcrumed on a bolt *m* in a bracket *m*', is operated by means of a cam *o* on the shaft of the impression-cylinder. The cam *o* has a 75 groove *o*', in which runs a roller *m*², carried at the end of the lever *l*. The fork *k* is also provided with antifriction-rollers *k*' *k*². The paper on the impression-cylinder is out of contact with the numbers of the numbering-wheels, except at certain raised parts which are made on the cylinder. These raised parts would be suitably positioned according to the nature of the work being done. When there are two sheets circumferentially arranged and numbered at each revolution of the impression-cylinder, then of course there would be two raised parts or sets of raised parts arranged at points diametrically opposite to one another. 80 85 90 95 100

105 On the drawings the impression-cylinder is shown as made with a longitudinal strip *p*, which may consist of a piece of vulcanized

fiber or other material let into a groove in the surface of the cylinder and in such manner as to lie flush therein. This groove is dovetailed, so as to hold the strip securely in place, and it also runs in a line which is exactly parallel with the axis of the cylinder. At the place where it is desired to print the numbers on the sheets of paper a piece of cloth or other like soft material *q* is secured to the strip *p*, so as to raise the surface of the cylinder at this spot sufficiently to insure the numbers of the numbering-wheel contacting with it, and consequently printing the paper when it passes over it. The numbers of the numbering-wheel do not contact with the paper at any other part of the cylinder. When two sheets are numbered at each revolution of the cylinder, then there are two insets *p* and two pieces *q*, one on each inset. If more sheets are printed at each revolution, then of course the raised places are increased accordingly. In order that the numbers may be printed consecutively, the gearing *f g*, connecting the impression-cylinder and the numbering-wheel shaft, would have wheels with unequal numbers of teeth. When two sheets are circumferentially arranged and printed at each revolution of the impression-cylinder, then there would be one wheel with forty-eight teeth and the other with fifty.

The numbering-disk *a* is fitted slidably upon the sleeve *d* and can be shifted to any desired position thereon and clamped by the screws *r r*. Of course when the disk is moved along the sleeve the raised piece *q* has to be removed and a raised part fitted at another point in the length of the strip *p*, which will correspond with the new position of the numbering-disk. The advantage of having the longitudinal strip *p* is thus easily seen, as it facilitates the accurate placing of the raised part or parts *q*. If there are two or more numbering disks or wheels *a*, then the lateral movement in order to bring the disks into proper printing position would have to be increased, and the increase may be effected by a second cam arrangement, which may be connected with the first and be so arranged as to shift the disks the proper distances at the proper times. This arrangement is shown at Fig. 4, where it will be seen that there are two disks *a a*, arranged side by side on the sleeve *d*. In this case the cam *o* has a second groove *o*², with which a pin *s'* of a bar *s* engages. This bar is slidably fitted in the machine-frame *t* and has a second pin *s*², which engages with a groove *u*' in a cam *u* on a spindle *v*, having a worm-wheel *v*', which is rotated by a worm *w* on a shaft *w*'. The shaft is carried in the frame-bracket *w*² and is rotated by means of suitable gearing. One of the disks may be adapted to print from "1" to "50" and the other from "51" to "100," and the parts of the mechanism are arranged so that whenever the printing up to

"50" has been accomplished the worm-gear *w v*' comes into action and causes the cam *u* to throw the "1" to "50" disk out of printing position and insert the other disk into position, so as to continue the printing up to "100," when the cam *u* is caused to throw out the "1" to "100" disk and reinsert the "1" to "50" disk.

Having now fully described our invention, what we claim, and desire to secure by Letters Patent, is—

1. In numbering mechanism the combination with a surface for receiving impressions of numbering means said means being automatically moved back and forward laterally so as to bring the numbers into correct printing position.

2. In numbering mechanism the combination with a surface for receiving impressions of a numbering-disk having numbers thereon said disk being automatically moved back and forward laterally so as to bring the numbers into correct printing position.

3. In numbering mechanism the combination with a surface for receiving impressions of numbering-disks having numbers thereon said disks being automatically moved back and forward laterally so as to bring the numbers into correct printing position.

4. In numbering mechanism the combination with a surface for receiving impressions of a numbering-disk having ridges with numbers thereon said disk being automatically moved back and forward laterally so as to bring the numbers into correct printing position.

5. In numbering mechanism the combination with a surface for receiving impressions of a numbering-disk having two parallel circumferential ridges thereon each ridge having a set of numbers said disk being automatically moved back and forward laterally so as to bring the numbers into correct printing position.

6. In numbering mechanism the combination with a surface for receiving impressions, of a numbering-disk, a sleeve, a shaft, and means for automatically moving the sleeve laterally on the shaft to move said disk back and forward in the direction of the length of said shaft.

7. In numbering mechanism the combination with a surface for receiving impressions, of a shaft, a sleeve on the shaft, a numbering-disk adjustably fitted on the sleeve, a lever for moving the sleeve laterally and means for operating the lever.

8. In numbering mechanism the combination with a surface for receiving impressions, of a shaft, a sleeve on the shaft, a numbering-disk adjustably fitted on the sleeve, a lever for moving the sleeve laterally, a cam for operating the lever and means for rotating the cam.

9. In numbering mechanism the combina-

- tion with a surface for receiving impressions of a strip let into said surface, a raised part on the strip, numbering means, and means for shifting said numbering means laterally.
- 5 10. In numbering mechanism the combination with a cylindrical surface for receiving impressions of a strip let into said surface along a line which is parallel to the axis of the cylindrical surface a raised part on the
- 10 strip, numbering means and means for shifting said numbering means laterally.
11. In numbering mechanism the combination with a surface for receiving impressions, of a shaft, a sleeve on the shaft, numbering-disks adjustably fitted on the sleeve, a lever for moving the sleeve laterally, a cam for operating the lever, means for sliding the cam and means for operating the said sliding means.
- 20 12. In numbering mechanism the combination with an impression-cylinder, of a shaft for said cylinder, a second parallel shaft, means for driving the second shaft from the first shaft, a sleeve on the second shaft, numbering-disks on the sleeve, a lever for moving the sleeve laterally on its shaft, a cam on the
- 25 cylinder-shaft for operating said lever, means for moving said cam laterally on its shaft, a second cam for operating said moving means and mechanism for rotating the second cam. 30
13. In numbering mechanism the combination with an impression-cylinder, of a shaft for said cylinder, a second parallel shaft, means for driving the second shaft from the first shaft, a sleeve on the second shaft, numbering-disks on the sleeve, a lever for moving the sleeve laterally on its shaft, a cam with two grooves slidably fitted on the cylinder-shaft, a bar with pin engaging one of the grooves, a second cam adapted to engage a second pin on the said bar and worm-gearing for operating said second cam. 35
